WARPING MACHINE

Theodore E. Carlson, Cumberland, Md., assignor
to Celanese Corporation of America, a corpora-
tion of Delaware

Application November 10, 1943, Serial No. 509,723

9 Claims. (Cl. 28—54)

This invention relates to warping machines, and relates more particularly to reeds for use on high speed section warping machines.

In high speed section warping machines, as heretofore commonly constructed, the yarn bore against the dent wires and/or bar guides at one point cutting nicks therein, which nicks caused the splitting of threads with a consequent impairment of the fabric made from such threads.

Another factor which contributed to lower considerably the efficiency of the prior reeds was that fly was caught in the reed wires filling up the spaces therebetween, causing further yarn damage and unequal yarn tensions.

It is an object of this invention to provide an improved reed for warping machines which will be free from the above mentioned and other disadvantages and which will be especially simple in construction and efficient in operation.

Another object of this invention is the provision of a vertically reciprocating reed having bent or curved wires employed in conjunction with horizontally disposed guides so as to cause the yarn to wipe or polish both wires and guides instead of cutting the same.

Other objects of this invention, together with certain details of construction and combinations of parts, will appear from the following detailed description and drawings.

In the accompanying drawings:

Fig. 1 is a front view, partly broken away, of a warping machine creel showing the reed and guide of my invention applied thereto.

Fig. 2 is an enlarged detail view in perspective of one unit of reed and guide shown in Fig. 1.

Fig. 3 is a detail view of a modification of the reed shown in Figs. 1 and 2 and shows the wires to be bent to an arc, and

Figs. 4 and 5 are detail views of other modifications of the reed.

Like reference numerals indicate like parts throughout the several views of the drawings.

While the reed and guide of my invention may be used in substantially all places where stationary reeds have heretofore been employed, for the sake of brevity and clarity it will be described in connection with the front reed on a high speed section warping machine.

Referring to the drawings, the reference numeral 1 generally indicates the frame of a warping machine broken away so that only one bank of reeds is shown. The frame as shown comprises an angle iron support 1, a base 2 and a top cross-piece or head 3. Cross bars 4, on which the reeds are mounted, may be welded or other-

wise attached to the support 1 and to any other braces, etc. (not shown) normally employed in such machines. On the base 2 is supported a speed reducer 5 on the input shaft 6 of which is fixed a pulley 7 driven from a motor (not shown) or other suitable source of power by a belt 8. The output shaft 9 of the speed reducer 5 carries a cam 11. A suitable bearing 12 and hand wheel 13 may be provided to support and manipulate, respectively, the output shaft 9.

The cam 11 cooperates with a cam follower 14 which is journaled in the bifurcated lower end 15 of rod 16. The rod 16 passes through a series of guides 17 attached to the cross bars 4. The rod 16 carries a plurality of arms 18 the length of which is governed by their position on the machine. The arms may be attached to the rod 16 by welding, set screws or other suitable means. Where the arms 18 are of considerable length they may be braced by means of bars 19, one of which is shown bracing the bottom arm 18 in Fig. 1. Mounted on the free ends of the arms 18 are rods 21 that operate in guides 22 attached to the cross bars 4. Each rod 21 supports a rack 23. As the rod 16 is reciprocated by the rotation of cam 11, the movement is imparted to the racks 23.

On the frame 1 and in alignment with each rack 23 is a block 24. The block 24 acts as a support for a plurality of horizontally disposed guide bars 25. On the machine shown in the drawing each block 24 supports a group of three guide bars 25, but a greater or smaller number of guide bars may be employed. These guide bars 25 extend past but in relatively close proximity to a reed frame 26 mounted in a groove 27 formed in the rack 23. The reed frames 26 may be of usual form. The reed frame 26 is provided with wires or dents 28, each dent being bent out of the vertical to form an obtuse angle as shown in Figs. 1 and 2; to form an arc as shown in Fig. 3; to form an open S as shown in Fig. 4; or bent through a number of smaller angles as shown in Fig. 5. Yarns 29 from a creel or other suitable supply (not shown) to be formed into a warp or the like are passed over the guide bars 25 and between the wires 28. There may be a yarn 29 over each guide bar 25 for each wire 28 as shown in Fig. 2, or a yarn may be passed over the top guide bar and between the first and second wires with the next adjacent yarn of the warp passed over the middle guide bar and between the second and third wires and so on, or any other method of threading the yarn through the guide bars and wires may be employed.

When the machine is in operation the reed frames 26 move up and down so that the yarn 29 moves along the wires 28 instead of bearing at one point and cutting them. With the reed frame 26 containing curved wires 28, angle wires, or multiple curve or angle wires, the yarn in the dent follows the wire and is moved back and forth laterally on the guide bar 25. Thus, instead of running in one place on the bar, the yarn polishes a path on the bar commensurate in width to the curve or angle of the reed wire over which the yarn operates. Therefore, neither the wires or guide bars have nicks cut therein but both are wiped and polished by the yarn, keeping the same free of lint or fly. Both the life of the reed and guide bars are thus prolonged as the cutting of nicks in either is substantially avoided. Furthermore, the continually polished reed and bar, being free from nicks, effects a substantial reduction in the production of split threads, and consequently a better grade of fabric is obtained.

It is to be understood that the foregoing detailed description is given merely by way of illustration and that many variations may be made therein without departing from the spirit of my invention.

Having described my invention, what I desire to secure by Letters Patent is:

1. In a machine for warping threads, a guide bar over which the threads are adapted to pass, a reed frame cooperating with said guide bar, wires in said frame for spacing said threads, said wires being bent and means for reciprocating said frame so as to cause said threads to move laterally relative to said guide bar and longitudinally relative to said bent wires.

2. In a machine for warping threads, a guide bar over which the threads are adapted to pass, a reed frame cooperating with said guide bar, wires in said frame for spacing said threads, said wires being bent and in the plane of said frame, and means for reciprocating said frame so as to cause said threads to move laterally relative to said guide bar and longitudinally relative to said bent wires.

3. In a machine for warping threads, a guide bar over which the threads are adapted to pass, a reed frame cooperating with said guide bar, wires in said frame for spacing said threads, said wires being bent and in the plane of said frame, and means for reciprocating said frame vertically so as to cause said threads to move laterally relative to said guide bar and longitudinally relative to the said bent wires.

4. In a machine for warping threads, a horizontal guide bar over which the threads are

adapted to pass, a reed frame cooperating with said guide bar, wires in said frame for spacing said threads, said wires being bent and in the plane of said frame, and means for reciprocating said frame vertically so as to cause said threads to move laterally relative to said guide bar and longitudinally relative to the said bent wires.

5. In a machine for warping threads, a horizontal guide bar over which the threads are adapted to pass, a reed frame cooperating with said guide bar, wires in said frame for spacing said threads, said wires being in the shape of an obtuse angle and being in the plane of said frame, and means for reciprocating said frame vertically so as to cause said threads to move laterally relative to said guide bar and longitudinally relative to the said bent wires.

6. In a machine for warping threads, a horizontal guide bar over which the threads are adapted to pass, a reed frame cooperating with said guide bar, wires in said frame for spacing said threads, said wires being in the shape of an open S and being in the plane of said frame, and means for reciprocating said frame vertically so as to cause said threads to move laterally relative to said guide bar and longitudinally relative to the said bent wires.

7. In a machine for warping threads, a horizontal guide bar over which the threads are adapted to pass, a reed frame cooperating with said guide bar, wires in said frame for spacing said threads, said wires being in the shape of an arc and being in the plane of said frame, and means for reciprocating said frame vertically so as to cause said threads to move laterally relative to said guide bar and longitudinally relative to the said bent wires.

8. In a warping machine, a plurality of horizontally disposed guide bars, a vertically reciprocating reed frame containing bent wires cooperating with said guide bar and means for reciprocating the reed frame, said reciprocating means comprising a rod and a cam for operating said rod, said reed frame being attached to said rod by arms extending laterally from said rod.

9. In a warping machine, a plurality of horizontally disposed guide bars, a vertically reciprocating reed frame containing bent wires cooperating with said guide bar, means for reciprocating the reed frame, said reciprocating means comprising a rod and a cam for operating said rod, said reed frame being attached to said rod by arms extending laterally from said rod, means connected to said arms and carrying a rack adapted to support said reed frame.

THEODORE E. CARLSON.
